AUTOMOBILE MOUNTED MOBILE HOME

Charles E. Van Bibber, 3312 Dublin Drive, El Paso, Tex.

Filed Jan. 26, 1961, Ser. No. 63,709

Term of patent 14 years

(CL. D14—3)

Fig. 3

Fig. 2

Fig. 4

Fig. 5

Fig. 1

FIG. 1 is a perspective view of an automobile mounted mobile home;

FIG. 2 is a side elevational view thereof;

FIG. 3 is a front elevational view thereof;

FIG. 4 is a top plan view thereof; and

FIG. 5 is a rear elevational view thereof.

Portions of an automobile shown in broken lines in FIG. 2 are included for illustrative purposes only.

I claim:

The ornamental design for an automobile mounted mobile home, as shown and described.
